CONCRETE BLOCK HANDLING DEVICE

Leon H. Schlough, Waite Park, and Wesley E. Schlough, St. Cloud, Minn., assignors to Northwest Concrete Products Co., St. Cloud, Minn., a corporation of Minnesota

Application November 10, 1949, Serial No. 126,558

4 Claims. (Cl. 214—75)

1

This invention appertains to material handling apparatus, and more particularly relates to an apparatus for handling heavy articles in the loading and unloading of trucks and semi-trailers.

A primary object of the instant invention is to reduce the time required for loading and unloading heavy articles on trucks and to simplify the loading operation.

Another important object of the invention is to provide a material handling device that can be easily installed on any type of truck or similar vehicle and that will permit a truck, so equipped, to be used for other general purposes.

Another important object of this invention is to provide a portable lifting and loading apparatus that, when mounted on a vehicle, will not add materially to the weight of the vehicle and will not encumber the movement of the vehicle nor destroy the general utility of the vehicle.

Another object of this invention is to provide a material handling apparatus, that is especially adapted for loading and unloading concrete blocks or similar devices on a truck, the stated loading and unloading operation being capable of being carried out by one operator without any physical hazards being present and without damage to the materials being handled.

These and ancillary objects and structural features of merit are attained by this invention, the preferred embodiment of which is set forth in the following description and illustrated in the accompanying drawings, wherein:

Figure 1 is a side elevational view of a truck, having a material handling apparatus of the present invention operatively mounted thereon;

Figure 2 is a rear elevational view;

Figure 3 is a transverse sectional view of the rail member, with the hoisting means being shown in elevation, and the carriage means being shown in rear elevation;

Figure 4 is a side elevational view of another form of hoisting cradle;

Figure 5 is an enlarged sectional view illustrating the means for locking the rail member to the bed; and

Figure 6 is a fragmentary sectional view of the means for rotatably mounting the rail member on the vertical support.

In the accompanying drawings, a portable support 10 is illustrated, the same constituting the rear load carrying portion of a truck or a semi-trailer and consisting of a chassis 12 mounted on wheels 15 and supporting a bed or platform 14. A post 16 is vertically mounted on one

2

end of the bed and preferably is disposed centrally between the opposing side edges of the bed. Rigidifying or brace bars 18 are bolted at their lower ends on the bed and are secured at their upper ends to the post. An axial bore or opening 20 is formed in the upper end of the post and a socket member 22 is seated in the inner end of the bore. Ball bearing units 24 and 26 are disposed within the bore, the units being vertically spaced by a sleeve 28.

An elongated rail member 30 is provided and tracks 32 and 34 are formed on the rail member. Means is provided for rotatably mounting the rail member on the support 16, so that the rail member swingably overlies the bed and is disposed in a horizontal plane. The means preferably includes a lateral head 36 formed on one end of the rail member, the head having a flat outer face 38 from which centrally projects an anchoring shaft or spindle 40. The spindle 40 is rotatably mounted in the ball bearing units, so that the outer end thereof is seated in the socket member 22, with the outer face of the head seated on the upper ball bearing unit.

A carriage 42 is mounted for movement on the rail member and includes a U-shaped support 44 having upwardly extending and outwardly inclined apertured legs 46 and 48. Flanged wheels 50 are mounted on stub axles 52 carried by the legs 46 and 48, so that the rail engaging portions of the wheels are rotatably seated on the tracks 32 and 34, the wheels being disposed in angular relation, whereby displacement of the carriage from the track is prevented.

Rigidifying means 54 is provided for the rail member and includes a vertical bar 56 which is mounted on the top of the rail member, substantially in the center thereof. Brace rods 58 and 60 are connected at their opposing ends on the rail member and bar 56, an adjustable turnbuckle 62 being operatively associated with the brace or truss rod 60.

Hoisting means 64 is swivelly suspended from and carried by the carriage and includes an electrically operated hoist 66 having a lug 68, which is formed integral with the casing, projecting upwardly therefrom and formed with an enlarged head 70. The lug is rotatably journaled on the web of the carriage, and the head 70 is seated on the inner surface thereof. A load cradle 72 is provided and includes a vertically disposed bar 74, on the upper ends of which is affixed a bracket member 76 within which are rotatably journaled pulleys 78. The hoisting cable 80 is trained around the pulleys 78 from the hoist. A bar 82

is transversely positioned on the bar 74, adjacent the lower end thereof, and a control or switch box 84 is mounted on the bar, conductors 86 extending from the box to the electric hoist, whereby the hoist can be remotely controlled through the switch box 84. A bar 88 is formed transversely on the lower end of the bar 74 and is provided with laterally extending, parallel end sections or members 90.

With respect to Figure 4, it is to be noted that a lifting fork attachment 92 is provided, the same being interchangeable with the lifting cradle 72 and including a vertical bar 94 upon which the switch or control box 84 is mounted, a support 96 extending laterally from the upper end and having a pulley 98 rotatably journaled thereon by means of complementary upstanding ears 100. A fork 102 projects outwardly from the lower end of the bar 94 in parallelism with the support 96 and is adapted to support a plurality of heavy articles, whereby the same may be raised through the hoist and cable 80 operatively entrained over the pulley 98.

With respect to the operation of the hoist, attention is directed to Figure 1, wherein it is to be noted that a supporting frame 104 is mounted on the frame and suspended below the frame. The housing 104 supports a prime mover 106, such as a conventional air-cooled gasoline engine, having a driving shaft 108. A conventional single-phase generator 110 is mounted in the housing and a clutch 112 connects the driving shaft 108 of the motor with the shaft 114 of the generator. Electrical conductors extend from the generator through the flexible cable 113 to a bracket 115 mounted on the inner end of the rail member. An electrical wire 116 is connected thereto and insulated from the rail member by an insulating block 118. A similar insulating block 120 supports the opposing end of the wire, the block being mounted on an angle member 122 affixed to the outer or free end of the rail member. Thus, the electrical wire 116 extends parallel with and above the rail member and is supported thereby. A contact arm 124 is bifurcated at its upper end and a roller 126 is rotatably journaled therein, the roller being in contact with the wire. The arm 124 is secured to the leg 46 of the carriage and the electrical current for the electric hoist is transferred thereby from the line 116 to the hoist.

Means is provided for supporting and locking the rail member in an inoperative position, preferably extending centrally above the bed 14. In this respect, a supporting frame 128 is provided and includes a pair of side bars 130 and 132 having inner converging upper ends between which is transversely positioned a bar 134 having a vertical opening 136 formed therein. A cross-bar 138 is connected to the side bars and the lower ends thereof are formed with lateral lugs 140 adapted to be received within openings formed in the end cross-member 142 of the chassis. A rod 144 is disposed through the opening 136 and is formed at its upper end with jaws 146 and 148. The jaws are commonly pivoted as at 150 to the upper end of the rod and are separately pivoted on transverse pivot pins 152 mounted in the opening 154 formed in the upper end of the bar 134. As seen in Figure 5, the jaws are adapted to grip upon the tracks 32 and 34 on the rail member, when the rod is in a lowered position. The rod is raised and lowered by means of a bifurcated actuating and locking member 156 pivotally mounted on the cross-bar

5

138. A chain 158 is suspended from a ring 160 formed on the outer end of the rail member and a hook 162 is formed on the lower end of the chain, the hook being adapted to be secured to the chassis or to the supporting frame 128. A chain tightener 164 is operatively associated with the chain.

In operation, a supporting screw or hydraulically actuated jack 166 is lowered about its pivot 168, whereby the same is secured to the chassis of the truck or vehicle, the jack maintaining the bed in a horizontal plane for unloading. The supporting frame 128 is then removed by raising the rod 144 to release the jaws from the boom or rail and the lower end of the supporting frame is detached from the vehicle chassis. The chain 158 is unlocked and the boom can then be swung about its journaled end. The cradle 72 is then attached to the articles, such as building blocks 170, by lowering the hoisting cable 80, through the control box 84 and the hoist 66. The cradle is then secured to the blocks and the cradle is raised by the hoist, whereupon the carriage is moved on the rail member, as the rail member is being swung outwardly beyond the bed. The "down" button on the control box 84 is then pushed and the articles are lowered into a resting position. The reverse operation of the hoist raises the load cradle and lifting arms from the load.

Of course, it is to be realized that any type of heavy articles may be loaded and unloaded on any type of vehicle merely by changing the type of cradle and lifting arms in order to meet the particular size and shape of the articles. Thus, since many other modifications and purposes of this invention will become readily apparent to those skilled in the art upon a perusal of the foregoing description, it is to be understood that certain changes in style, size and components may be effected without a departure from the spirit of the invention and within the scope of the appended claims.

Having described the invention, what is claimed as new is:

1. A material-handling apparatus for loading and unloading heavy articles comprising a platform, a vertical support extending from the platform, a rail member rotatably mounted at one end on the support, said member swingably overlying the platform and disposed parallel therewith, a carriage mounted on the rail member for movement thereon, electrically operated hoisting means swivelly suspended from the carriage, a motor for operating said hoisting means, an electrical conductor supported by the rail member, means carried by the carriage and contacting the conductor for supplying electrical energy to the hoisting means, means for locking the rail member on the platform, and means carried by said hoisting means operable to control the operation of said motor.

2. In a material-handling apparatus for loading and unloading heavy articles on a flat bed truck, a vertical support mounted on the bed adjacent one end, an elongated rail member swingably mounted on the support for swinging movement in a horizontal plane overlying the bed, a roller carriage mounted on the rail member, hoisting means, prime mover means for operating said hoisting means, means for swivelly suspending the hoisting means from the carriage, means for locking the rail member on the bed, and means for operating said prime mover remotely therefrom and at said hoisting means,

5

55

60

70

75

said hoisting means including an electric hoist, a load cradle operatively carried by the hoist, an electrical conductor supported by the rail member and disposed parallel therewith and contact means carried by the carriage for transferring electrical current from the conductor and through the carriage to the hoist.

3. In a material-handling apparatus for loading and unloading heavy articles on a flat bed truck, a vertical support mounted on the bed adjacent one end, an elongated rail member swingably mounted on the support for swinging movement in a horizontal plane overlying the bed, a roller carriage mounted on the rail member, hoisting means, prime mover means for operating said hoisting means, means for swivelly suspending the hoisting means from the carriage, means for locking the rail member on the bed, and means for operating said prime mover remotely therefrom and at said hoisting means, 15 said means for swivelly suspending the hoisting means including a lug extending upwardly therefrom, an enlarged head on the lug, said lug being disposed through a vertical opening in the bottom of the carriage, the head being disposed on the inner surface of the bottom.

4. In a material-handling apparatus for loading and unloading heavy articles on a flat bed truck, a vertical support mounted on the bed adjacent one end, an elongated rail member swingably mounted on the support for swinging move- 20 25 30

ment in a horizontal plane overlying the bed, a roller carriage mounted on the rail member, hoisting means, prime mover means for operating said hoisting means, means for swivelly suspending the hoisting means from the carriage, means for locking the rail member on the bed, and means for operating said prime mover remotely therefrom and at said hoisting means, said locking means including a supporting frame in spaced relation to said vertical support, said supporting frame including a bar for receiving a free end of said rail, releasable clamp means carried by said support frame for clamping said rail to said bar.
